No. 37,127.

Patented September 13, 1904.

UNITED STATES PATENT OFFICE.

SIDNEY A. KELLER, OF NEW YORK, N. Y.

DESIGN FOR A HANDLE FOR PAPER-CUTTERS OR SIMILAR ARTICLES.

SPECIFICATION forming part of Design No. 37,127, dated September 13, 1904.

Application filed August 20, 1904. Serial No. 221,582. Term of patent 3½ years.

To all whom it may concern:

Be it known that I, SIDNEY A. KELLER, a citizen of the United States, and a resident of New York, borough of Manhattan, in the county of New York and State of New York, have invented a certain new, original, and ornamental Design for the Handle of a Paper-Cutter or Similar Article, of which the following is a specification.

10 The accompanying drawing is a view in elevation of the handle of a paper-cutter having my design applied thereto.

What I claim is—

The ornamental design for the handle of a paper-cutter or similar article, as shown.

SIDNEY A. KELLER.
